UNITED STATES PATENT OFFICE.

CHARLES E. FANNING, OF DAVENPORT, IOWA, ASSIGNOR TO JOHN G. SORENSEN, OF DAVENPORT, IOWA.

VENDING-MACHINE.

1,087,748.

Specification of Letters Patent.

Patented Feb. 17, 1914.

Application filed June 12, 1912. Serial No. 703,147.

To all whom it may concern:

Be it known that I, CHARLES E. FANNING, a citizen of the United States, and a resident of the city of Davenport, county of 5 Scott, and State of Iowa, have invented certain new and useful Improvements in Vending-Machines, of which the following is a specification.

My invention relates to improvements in 10 vending machines and has for its object the provision of a vending machine of improved construction and operation and one which is adapted to vend various articles not vendible by the ordinary vending machines now 15 in use.

A further object of my invention is to provide a machine of this character which is simple of construction and convenient and efficient in use.

20 The invention consists in the combinations and arrangements of parts hereinafter described and claimed.

The invention will be best understood by reference to the accompanying drawings 25 forming a part of this specification, and in which—

Figure 1 is a side elevation of a vending machine embodying my invention, Fig. 2, a section taken on line $x-x$ of Fig. 1, Fig. 30 3, a section taken on line $y-y$ of Fig. 4, Fig. 4, a front elevation of the machine shown with portions broken away for the sake of clearance, Fig. 5, a detail view of the check or coin chutes employed in the 35 machine, Fig. 6, a detail of a bar employed to open the different vending compartments of the machine simultaneously, Fig. 7, a bar employed in the machine to simultaneously reset slide members employed in the 40 machine, Fig. 8, an enlarged horizontal section taken on line $z-z$ of Fig. 4 and Fig. 9, a top plan view of the machine with a portion broken away for the sake of clearance.

45 The preferred form of construction, as illustrated in the drawings comprises a suitable casing 1 which is divided by horizontal partitions 2 into a plurality of superposed vending compartments opening at one side 50 of casing 1. Each of these vending compartments is adapted to contain a single article of merchandise and is closed by an individual door 3. Each of the doors 3 is provided with an operating knob 4 and an

inwardly extending latching projection 5 55 having a latching notch 6 therein. Each of the latching notches 6 is adapted to receive an inwardly turned end 7 of a corresponding latching lever 8 which is pivotally mounted at the front of casing 1 and is 60 normally held in depressed position by means of a spring 9. Each of the latching projections 5 is provided with a beveled or 65 pointed nose, adapted to automatically elevate the corresponding lever ends 7 so as to 70 cause engagement thereof with the corresponding notch 6 upon closing of each of the doors. A spring 10 is provided in each 75 of the compartments in casing 1 and contacts with the inner side of the corresponding door to force said door open when released. The three uppermost doors 3 are provided with inwardly projecting supporting shelves 11 which are adapted to support the articles contained in the corresponding compartments and carry such articles outwardly when said doors are opened 80 so as to facilitate delivery of said articles. By this arrangement it will be observed that upon elevation of the corresponding latching lever 8 the door of the corresponding compartment will automatically open to permit discharge or delivery of the article contained in said compartment.

A vertically sliding release bar 12 is arranged in the forward portion of casing 1 and is provided with a plurality of laterally projecting release pins 13, each of said release pins resting under one of the latching ends 7 of levers 8. Release bar 12 extends 85 to the top of the casing 1 where it is provided with a forwardly turned end 14 which facilitates manual elevation of said bar. Casing 1 is provided with a removable cover 15 which affords access to the upper end 90 of release bar 12. By this arrangement it will be observed that upon elevation of release bar 12 all of the latching levers 8 will be elevated simultaneously and all of the closed doors 3 simultaneously opened, 95 thus facilitating recharging of the machine.

A main check or coin chute 16 is arranged to extend vertically at the front of the machine and a plurality of individual check or coin chutes 17 are arranged substantially 105 horizontally at the side of main chute 16 to discharge therein, there being one of the individual check chutes 17 to correspond with

each of the latching levers 8 as shown. Each of the latching levers 8 is provided with a pin 18 projecting forwardly through a slot 19 provided in plate 20, which constitutes 5 the rear of the check chutes, each of the pins 18 being so positioned that the passage of a check or coin through the corresponding individual chute 17 and into chute 16 will elevate the pin and consequently the corresponding latching lever 8. Suitable entry openings 21 are provided for the insertion of checks or coins in the chutes 17 and a slide member 22 is arranged to reciprocate in each of said chutes 17 to force an inserted 10 check or coin through the corresponding chute 17 and discharge the same into chute 16. Each of the slides 22 is provided with an operating knob 23 projecting forwardly through a slot 24 provided in the front plate 20 of the casing 1. Each of the slides 22 is held normally in retracted and depressed position by means of a spring 25 which is secured at one end to a bar 26 carried by an inwardly projecting post 27 and at its other 15 end to a suitable flange provided in casing 1. The post or pin 27 on each of the slides 22 is adapted to automatically engage a corresponding locking notch 29 in a vertically reciprocatory locking and release bar 30, arranged in casing 1, as shown. A bar 30 is held normally in elevated position by means of a tension spring 31 which is made strong enough to resist the tension of the different springs 25, but which may be 20 manually depressed to release pins 28 from notches 29, as will be readily understood. By this construction, it will be observed, that when slides 22 are forced to the left by means of knob 23, a check or coin inserted 25 in the corresponding chute 17 will be forced out of said chute and into chute 16 thus elevating the corresponding latching lever 8 and opening the door 3 to the corresponding vending compartment in the casing 1. Upon completion of such movement of slide 22, pin 27 thereon automatically rides into the corresponding notch 29 and locks said slide against retraction by spring 25 thus closing the corresponding opening 30 30 against insertion of another check or coin. When the machine is empty, or when it is desired to recharge or reset the same for any reason, depression of bar 30 will release all of the slides 22 which have thus 35 been placed in sealing or locking position and permit their return to normal position under the influence of springs 25. A locked drawer 32 is arranged in the lower portion of casing 1 to receive checks or coins from 40 chute 16.

By the construction above set forth, it will be observed, that various articles of merchandise, such as pies, cakes, or packages of candy may be sold, and that the 45 same will be delivered in good condition and

without being damaged by contact with each other. The specific form of construction employed is simple and efficient in use.

While I have illustrated and described the preferred form of construction for carrying my invention into effect, this is capable of variation and modification without departing from the spirit of the invention. I, therefore, do not wish to be limited to the precise details of construction set forth, 75 but desire to avail myself of such variations and modifications as come within the scope of the appended claims.

Having described my invention what I claim as new and desire to secure by Letters Patent is:

1. A vending machine comprising a casing; a plurality of compartments therein; a separate door for each compartment; a separate catch for holding each of said doors closed; automatic means for opening said doors when released; means for releasing said catches separately; and means for releasing said catches simultaneously, substantially as described. 90

2. A vending machine comprising a casing; a plurality of compartments therein; a separate door for each compartment; a separate catch for holding each of said doors closed; automatic means for opening said doors when released; means for releasing said catches separately; and manually operable means for releasing said catches simultaneously, substantially as described. 95

3. A vending machine comprising a casing; a plurality of compartments therein; a separate door for each compartment; a separate catch for holding each of said doors closed; automatic means for opening said doors when released; means for releasing said catches separately; means for releasing said catches simultaneously; and a locked door giving access to said last mentioned means, substantially as described. 100

4. A vending machine comprising a casing; a plurality of compartments therein; a separate door for each compartment; a separate catch for holding each of said doors closed; automatic means for opening said doors when released; means for releasing said catches separately; manually operable means for releasing said catches simultaneously; and a locked door giving access to said last mentioned means, substantially as described. 110

5. A vending machine comprising a casing; a plurality of compartments therein; a separate door for each of said compartments; a separate catch for holding each of said doors closed; a spring arranged to throw each of said doors open upon release of the corresponding catch; means for releasing said catches separately; and means for releasing said catches simultaneously, substantially as described. 120

6. A vending machine comprising a casing; a plurality of horizontal partitions in said casing dividing the same into a plurality of separate compartments; a swinging door 5 for each compartment; a latching projection on each of said doors having a beveled nose and a notch therein; a spring held latch for each of said projections arranged to be struck by the beveled nose thereon and 10 automatically engage said notch to lock the corresponding door closed; and a longitudinally movable member engaging each of said latches and arranged to release all of said catches upon longitudinal movement 15 thereof, substantially as described.

7. A vending machine comprising a casing; a plurality of horizontal partitions in said casing dividing the same into a plurality of separate compartments; a swinging

door for each compartment; a latching projection on each of said doors having a beveled nose and a notch therein; a spring held latch for each of said projections arranged to be struck by the beveled nose thereon and automatically engage said notch to lock the 20 corresponding door closed; a longitudinally movable member engaging each of said latches and arranged to release all of said catches upon longitudinal movement thereof; and a locked door giving access to said 25 member, substantially as described.

In testimony whereof I have signed my name to this specification in the presence of two subscribing witnesses.

CHARLES E. FANNING.
